HOOP TOY

Robert Catron, 5718 Cambridge St.,
St. Louis Park, Minn. 55416

Filed May 12, 1971, Ser. No. 142,857

Term of patent 14 years

Int. Cl. D21—01

U.S. Cl. D34—15 G

FIG. 1 is a side elevational view of the hoop toy showing my new design;

FIG. 2 is a front view of FIG. 1;

FIG. 3 is a sectional view taken along line 3-3 of FIG. 1;

FIG. 4 is a side elevational view of a hoop toy showing a first modification of my new design;

FIG. 5 is a front view of FIG. 4;

FIG. 6 is a sectional view taken along line 6-6 of FIG. 4;

FIG. 7 is a side elevational view of a hoop toy showing a second modification of my new design;

FIG. 8 is a front view of FIG. 7; and

FIG. 9 is a sectional view taken along line 9-9 of FIG. 7.

I claim:

The ornamental design for a hoop toy, substantially as shown and described.
